UNITED STATES PATENT OFFICE.

DONALD NOBLE, OF BRIDGEPORT, CONNECTICUT, ASSIGNOR TO THE SINGER MANUFACTURING COMPANY, A CORPORATION OF NEW JERSEY.

SEWING-MACHINE.

1,128,491.

Specification of Letters Patent. Patented Feb. 16, 1915.

Application filed October 30, 1913. Serial No. 798,188.

To all whom it may concern:

Be it known that I, DONALD NOBLE, a citizen of the United States, residing at Bridgeport, in the county of Fairfield and State of Connecticut, have invented certain new and useful Improvements in Sewing-Machines, of which the following is a specification, reference being had therein to the accompanying drawings.

10 This invention relates to improvements in sewing machines, and has for its object to adapt rotary loop-takers of the class represented by United States Patent No. 480,181, of August 2, 1892, to W. F. Dial, to the 15 oscillating system.

It is common knowledge that in the construction of lock-stitch sewing machines employing a rotary loop-taker having a cast-off portion, in connection with a take-up for drawing up the thread-loop and setting the stitch, it is essential to the action of the take-up that the loop-taker be given a variable motion or a multiple of rotations to one 25 complete actuation of the needle, and that in the construction of sewing machines employing oscillating loop-takers of the cast-off variety, as distinguished from the shuttle variety, it is common to locate the mass of under thread eccentric to the axis of oscillation of the loop-taker, so as to effect an 30 earlier take-up action and thus avoid the necessity of giving the loop-taker a variable motion or a multiple of actuations to one complete actuation of the needle, as in the 35 rotary type.

In the present construction applicant has effected a stitch-forming mechanism of the cast-off oscillating type which employs the large centrally located bobbin of the rotary 40 type, and in doing so has furnished a stitch-forming mechanism of the cast-off oscillating type which can be employed to the same advantage as the rotary type whenever the latter is impractical of use, as in the Singer 45 type of blind stitch sewing machine and in crank hemstitch machines employing a stitch-forming mechanism controlled to direct the seam formation at any angle to the seam last formed.

In the employment of loop-takers and 50 bobbin-cases as herein, the flange of the bobbin-case is provided with a notch or opening located with relation to the movements of the needle and loop-taker so that when the latter engages the needle-thread loop it carries its inner half or member against one of the walls of the notch, and in the further oscillation of the loop-taker the inner half of the loop is carried toward the center of oscillation where it remains during the expanding 55 of the loop, the other half of the loop crossing the outer face of the bobbin-case and finally cast off the loop-seizing member of the loop-taker when the take-up acts to draw the loop out through the notch and 60 into the fabric.

For the reason that the notch is stationary with respect to the oscillating movements of the loop-taker, the loop of needle-thread must leave the bobbin-case at the same point 70 that it enters, and in effecting this it is preferred that the loop-taker be given oscillatory movements of slightly more than a complete rotation and its speed slackened at the time that the loop is being withdrawn from 75 the notch, as in the present construction.

In the accompanying drawings illustrating the invention, Figure 1 is a plan view partly in full lines and partly in section, of a Singer blind-stitch sewing machine 80 equipped with the present invention; Fig. 2 a perspective of the front end portion of the oscillating cylinder into which is mounted the loop-taker, the throat or needle-plate being shown in dotted lines; Figs. 3, 4 and 5 85 perspective views of the loop-taker, bobbin-case and throat or needle-plate respectively; Fig. 6 an enlarged view of the thread-receiving end of the bobbin-case latch and Figs. 7, 8, 9, 10 and 11, views illustrating the 90 relative action of the loop-taker, bobbin-case and sewing thread when forming the stitch.

The present invention is shown as applied to a Singer blind-stitch sewing machine but as it is confined to the construction and application of the stitch-forming mechanism, only such reference will be made to the other 95 elements of the machine as is deemed necessary.

sary for a proper understanding of its application.

Referring to the figures, 1 represents the sewing machine frame in which is mounted in suitable bearings the main-shaft 2 carrying at one end the belt-pulley or hand-wheel 3 and at its opposite end the shaft-flange 4.

5 represents the oscillating cylinder having formed integral with it a bearing stud 6, shown in dotted lines only Fig. 1, mounted in a suitable bearing (not shown) formed in said frame, said stud being held against endwise movement, by nuts, as 7.

10 Mounted to move endwise in suitable bearings formed in the cylinder 5 is a needle-carrying bar 8 provided at its forward end with a needle-bracket 9 in which is suitably secured a needle 10, and coacting with said needle is an oscillating thread carrying 15 loop-taker 11 provided with the usual bobbin 12, said loop-taker having formed integral with it a hollow loop-taker shaft 13 mounted in a flange bushing 14 secured in an opening 15 formed in the cross-head 16 of 20 the cylinder 5.

25 17 represents a screw-bolt which passes through the base of the loop-taker and through the hollow loop-taker shaft and is threaded into a spirally threaded loop-taker 30 oscillating shaft 18, a suitable tongue 18' and notch (not shown) acting to hold the shafts 13 and 18 in given relationship.

35 19 represents a screw-stud threaded into a suitable bearing formed in the cross wall 20 of the cylinder 5 and secured by nut 21, the forward end of said stud being provided with a flange 22 and suitable bearing (not shown) entering a suitable opening formed 40 in said looper-oscillating shaft, and against the inner end of the latter rests said flange.

45 Upon the crank 23 threaded into the shaft-flange 4 is fulcrumed one end of the needle-bar actuating connection comprising an externally threaded connection 24 and internally threaded connection 25, the latter receiving the threaded end of the connection 24 and provided with a bearing 26 in which is mounted a short shaft 27 having formed integral with it a bearing 28 in which is secured by pinch screw 29 the needle-carrying bar 8. The opposite end of the shaft 27 has formed integral with it a collar 30 provided with a spirally threaded opening 31, shown in dotted lines only Fig. 1, which 50 acts with the spirally threaded looper-oscillating shaft 18 to oscillate the loop-taker.

55 From the foregoing it is to be understood that the element 27 is provided with integrally formed means for giving to the shaft 18 oscillatory movements, and that through the shaft-flange 4 and connections 24 and 25, stitch-forming movements are transmitted to the needle 10, which, as will be obvious, coacts with the loop-taker to form stitches.

To effect stitches in different planes, as in 65 the present construction, the main-shaft 2 is provided with a gear-member 32 which meshes with a gear-member 33 carried by the shaft 34 and as said gears are of the ratio of one to two, the shaft 34 is given one 70 rotation to two of the shaft 2. Upon the end of the shaft 34, opposite to that carrying the gear-member 33, is secured a flange 35 carrying a pin 36 having its axis eccentric to the axis of said shaft, and swiveled 75 on said pin is a block 37, shown in dotted lines only Fig. 1, which works in a suitable groove (not shown) formed in the extended portion 38 of the cylinder 5, thus transmitting to the latter oscillatory movements for 80 effecting stitches in different planes.

85 As the cloth feeding mechanism is unimportant to an understanding of the present invention, it is not deemed necessary to refer to it in detail, and, accordingly, the elements shown in Fig. 1 forming a part of such mechanism are designated by the numeral 39.

40 represents a forward extension of the cylinder 5 to the front edge of which is secured by suitable screws (not shown) passing through the openings, as 41, and threaded into the openings, as 42, the throat or needle-plate 43 provided with the needle opening 44 and bobbin-case stop member, 95 the latter comprising the wall 45 of the cut out portion 46 of said needle-plate. The loop-taker 11 is provided with a groove 47 which extends for a short distance into the loop-seizing member 48, as shown by dotted 100 lines Fig. 3, a part of said groove being located in the removable loop-taker gib 49, secured by screws, as 50.

51 represents the bobbin-case provided with the flange 52 which in practice is tracked by 105 the groove 47 of the loop-taker, the gib 49 comprising convenient means for entering and securing said bobbin-case in said loop-taker, said bobbin-case having formed integrally with it the stop walls 53 and 54 which 110 are caused to contact the respective stationary stop-members 45 and 55 by the reversing action of the loop-taker, later to be explained.

56 represents the bobbin-case post provided with a bobbin-retaining latch 57 having thread openings 58 and 59, the needle-thread 60 being passed from the supply to the needle 10 in the usual manner and the bobbin-thread 61 led from the bobbin 12 to 120 the openings 62, 63, 59 and 58, respectively, to the needle opening 44 in the needle-plate 43.

115 Referring to Fig. 7 the loop-seizing point 64 of the loop-seizing member 48 is shown 125 in its limit of oscillation in the direction indicated by the arrow *t* or in position to be advanced into the needle-thread loop 65,

as shown in Fig. 8, the continued oscillation of the loop-taker in the direction indicated by the arrow U, Fig. 8, causing the thread loop to be carried into the throat 65' and its inner member 66 to be caught by the walls 67 of the notch or opening 68 in the flange 52, thus carrying said member back of the bobbin-case and toward the axis of oscillation of the loop-taker, as shown in Fig. 9.

5 In the further oscillation of the loop-taker, the front arm 69 of the thread loop is, by the cast-off flange 69' of the loop-taker caused to move across the face of the bobbin and bobbin-case to the position shown in Fig. 10, with the arm 66 in substantially like position back of said bobbin-case, when the take-up 70 commences to draw the loop off the loop-seizing member 48 and through the opening 68 as shown in Fig. 11 and into the material being acted on, and at substantially 20 the time the take-up withdraws the loop out through said opening the needle-bar and loop-taker are caused to reverse their movements and during the time that the loop-taker is being oscillated back to its position shown in Fig. 7, the needle is being advanced to its limit of fabric-piercing movement, as shown in Fig. 1, when subsequent stitch is formed just as described.

30 During the time that the loop-taker is being oscillated in the direction indicated by the arrow U, Fig. 8, the stop wall 53 is in engagement with the stop-member 45, thus effecting an opening between the stop wall 35 54 and stop-member 55 for the passage of the thread-loop as shown by Figs. 8, 9 and 10, and when oscillated in the opposite direction the wall 54 is in engagement with the stop-member 55 thus effecting an opening 40 between the wall 53 and stop-member 45 for the passage of the loop, as shown in Figs. 7 and 11, and in the present construction the loop-taker is given oscillatory movements of slightly more than one complete rotation.

45 From the foregoing it is to be understood, that in the present construction of oscillating loop-taker there is employed a stationary central bobbin-case journaled in the loop-taker, which latter casts the outer half of the 50 thread-loop across the face of the bobbin-case while the latter acts to direct the inner half of said thread-loop across the rear side of said bobbin-case, and that dwells occur in the oscillating movement of the loop-taker, and that the reversing movements of the loop-taker effect openings for the free passage of 55 the thread-loop about the bobbin-case.

60 In Fig. 7, the character *a* denotes the position of the loop-seizing point 64 at the completion of its oscillatory movement in

the direction indicated by the arrow *t*, and *b* the position of said point at the completion of its like movement in a direction opposite to that indicated by said arrow.

The term "stationary" as herein employed in connection with the bobbin-case 70 will be understood to mean "practically stationary," the very slight movement of the bobbin-case, hereinbefore referred to, to open the thread-passages for the needle-loops being of such small extent that in the 75 art generally such bobbin-case is termed "stationary bobbin-case."

Having thus set forth the nature of the invention, what I claim herein is:

1. In a stitch-forming mechanism for sewing machines, the combination with a needle, a loop-taker provided with a loop-seizing member, a cast-off flange and a throat, and a stationary bobbin-case journaled in and upon and concentric with the same axis as 80 said loop-taker and about its periphery provided with a flange cut away for a portion of its length to provide a notch through which one-half of the needle-thread loop passes, of means for giving to said loop-taker oscillating movements, each oscillating movement being substantially only one 85 complete rotation, whereby it is timed to insure that the inner half of said thread-loop will enter said notch during the oscillation of said loop-taker in a direction to cast the thread-loop about said bobbin-case and to be withdrawn from said notch during the return movement of said loop-taker. 90

2. In a stitch-forming mechanism for sewing machines, the combination with a needle, a loop-taker provided with a loop-seizing member, a cast-off flange and a throat, and a stationary bobbin-case journaled in and upon and concentric with the same axis as 100 said loop-taker and about its periphery provided with a flange cut away for a portion of its length to provide a notch through which one-half of the needle-thread loop passes, of means including coacting spiral 105 gear members for giving to said loop-taker oscillating movements of sufficient amplitude to insure that said loop-taker will not interfere with the inner half of the thread-loop entering and emerging from said notch 110 during the formation of the stitch. 115

3. In a stitch-forming mechanism for sewing machines, the combination with a needle, a loop-taker provided with a loop-seizing member, a cast-off flange and a throat, and a stationary bobbin-case journaled in and upon and concentric with the same axis as 120 said loop-taker and about its periphery provided with a flange cut away for a portion of its length to provide a notch through which one-half of the needle-thread loop passes, of means for giving to said loop-taker oscillating movements of sufficient am- 125

plitude to insure that said loop-taker will not interfere with the inner half of the thread-loop entering and emerging from said notch during the formation of the 5 stitch and coacting stop elements controlled to effect a free passage of the thread-loop about said bobbin-case.

In testimony whereof, I have signed my name to this specification, in the presence of two subscribing witnesses.

DONALD NOBLE.
